UNITED STATES PATENT OFFICE

JOHN C. ROMBACH, OF GLENDALE, CALIFORNIA, ASSIGNOR TO LAWRENCE D. BELL,
OF LOS ANGELES, CALIFORNIA

CIGAR AND CIGARETTE LIGHTER

Application filed February 15, 1928. Serial No. 254,460.

My invention is a cigar or cigarette lighter of the type having a wick which becomes saturated with a readily inflammable liquid, such as alcohol, and in which a spark is made 5 by a friction or file type of wheel acting on a flint, the spark igniting the liquid fuel.

An object of my invention in the type of lighter above specified is a power mechanism which, when liberated, actuates the 10 friction wheel; and in this connection a detailed object of this feature is to have a spring motor type of device which is always under a certain tension, but which manually may have the tension increased, and, after 15 such action, the spring is released and mechanically operates as a spring motor to operate the friction wheel.

Another object of my invention is having a lighter provided with a cap or cover which 20 encloses the wick. This cap or cover is manually opened by a longitudinal movement of actuating mechanism contained within the lighter and operated by a button or other device extending outwardly from the lighter.

25 In this connection a more detailed object is the tensioning of the spring motor to give the operative tension to work the friction wheel.

Another object of my invention is the construction of a lighter in the form of a relatively long tubular article or casing with the exposed wick, friction wheel and flint at the top, and immediately below these elements there is a relatively large chamber for the 30 liquid fuel and below such chamber, compartments for the spring motor and the mechanism immediately connected thereto.

Relative to these features, a more detailed object of my invention is to construct the 40 lighter in a tubular form somewhat resembling a fountain pen in shape and appearance, with the exposed part of the wick, the flint and the friction wheel housed under a folding or hinged cover or closure, and with 45 the main portion of the fluid chamber immediately below the exposed part of the wick so that there will not be a long wick through which the fluid must be conducted by capillary attraction to the exposed part.

50 Another object of my invention in a lighter

of the type above described is in the construction of liquid-tight compartments or receptacles within the main casing, to house the spring motor and the operative parts connected therewith, this arrangement being 55 such that the motor and the shaft driven thereby may be inserted through the bottom of the tubular casing. And a detail object in this feature is in having a removable base casing containing parts of the spring motor 60 and the elements associated therewith, this being completely cut off from the liquid chamber.

A general object in view in constructing the lighter as above mentioned is to make this 65 in a compact and convenient shape for carrying in a pocket or for ladies to carry in a handbag, and providing a lighter which may be manipulated readily by one hand; and, in addition, providing a safety factor by the 70 closable cover which, on release of the manually operated button construction, automatically closes, and extinguishes the flame, the construction having factors to make for the cleanliness thereof allowing ready filling 75 with an inflammable liquid but preventing leakage of such liquid.

In constructing my cigar or cigarette lighter, I preferably use a tubular container or housing which has an inner tubular compartment running completely therethrough, with an enlargement at the bottom. The casing has partitions or diaphragms at the top and the bottom, forming a closure, and in the enlargement of the compartment, there is 80 mounted a spring motor with a shaft extending to the friction wheel above the upper partition. Mounted in one side of the upper part of the casing, there is a spring mounted on a transverse pin, the end of this spring 85 thrusting on a flint which is slidably mounted, the flint bearing against the friction wheel and being positioned to light the exposed part of the wick extending upwardly through the upper partition from the fuel 90 chamber.

A second internal tubular passage is formed in the main casing and this houses a fixed rod on which is mounted a button type of device 95 extending through a slot in the outer casing, 100

this button type of device being connected to a sleeve. Attached to the bottom of the casting there is a base cap or casing structure having a block or nut-like device with opposite helical threads. This block is connected by a ratchet to the spring motor and such block is actuated by an upward movement of the button device, the sleeve connected thereto operating the yoke engaging the helical threads. The upward movement of the button also, by means of a rack and pinion connected to the cover at the top, opens such cover and exposes the wick.

The spring of the motor is given an initial tension but, as above mentioned, the movement of the button causes an increased tension of this, which, on the full movement of preferably a half turn, is released so that the shaft leading to the friction wheel may be rotated, this giving the spark, and having stop devices which allow the spring to return to its original tension. On release of the button the spring automatically retracts the yoke operating the threaded block and also retracts the racks operating the segmental pinion, thereby closing the cover, thus extinguishing the flame.

Various other details will be apparent as the description proceeds.

30 My invention will be more readily understood from the following description and drawings, in which:

Figure 1 is an elevation of my invention as if taken in the direction of the arrow 1 of Fig. 3.

Figure 2 is an elevation taken in the direction of the arrow 2 of Fig. 3 with certain parts at the top and bottom broken open to show the interior construction.

40 Figure 3 is an irregular section taken substantially on the line 3—3 of Fig. 11 in the direction of the arrows.

Figure 4 is an elevation similar to Fig. 1 with the cover open and interior parts exposed.

Figure 5 is a plan of the device taken in the direction of the arrow 5 of Fig. 1.

Figure 6 is a horizontal section on the line 6—6 of Fig. 3 in the direction of the arrows through the cap.

Figure 7 is a horizontal section on the line 7—7 of Fig. 3 in the direction of the arrows through the upper part of the liquid container.

55 Figure 8 is a horizontal section on the line 8—8 of Fig. 3 in the direction of the arrows showing in section the part slightly above the operating button.

Figure 9 is a horizontal section on the line 60 9—9 of Fig. 3 in the direction of the arrows showing the upper part of the spring motor clutch.

Figure 10 is a horizontal section on the line 65 10—10 of Fig. 3 in the direction of the arrows showing an abutment block in section

and the spring motor release and the yoke for winding the motor in plan.

Figure 11 is a horizontal section on the line 11—11 of Fig. 3 in the direction of the arrows showing a section through the yoke and the threaded block for winding the spring motor, and a pawl for controlling the motor shaft, the latter being in plan.

Figure 12 is a horizontal section on the line 12—12 of Fig. 3 in the direction of the arrows illustrating the pawl and ratchet for restraining the motion of the motor shaft.

Figure 13 is a section on the line 13—13 of Fig. 3 in the direction of the arrows illustrating mainly the body of the liquid chamber with the tubular housings extending therethrough.

Figure 14 is an elevation of a number of parts utilized in connection with the spring motor, these being shown disassembled and in somewhat their relative position.

Figure 15 is an underneath view of one of the clutches of Fig. 14 on the line 15—15 of such figure.

Figure 16 is a plan view of one of the clutches of Fig. 14 on the line 16—16 in the direction of the arrows.

Figure 17 is a vertical sectional view similar to the lower section of Fig. 2 with the parts in another position.

Figure 18 is an underneath view of the closure cap.

Figure 19 is an elevation of the rack for opening the cover, the cover being shown in part section.

Figure 20 is a plan of the rack of Fig. 19 as if taken on the line 20—20 in the direction of the arrows.

Figure 21 is an elevation of the flint support and the flint tension spring.

Figure 22 is a view of Fig. 21 in the direction of the arrow 22.

My invention utilizes what may be termed as a main casing 11, which, for the most part, is preferably cylindrical. This has an upper partition 12 rigidly secured thereto and a lower partition 13. This casing, with the partitions, forms a liquid-tight container except where it has openings, hereunder detailed, for filling and for the wick. This casing structure, it will be noted, is connected to the upper partition in a recessed portion 14 and fits against an annular shoulder 15 on the lower partition 13. (Note Fig. 3). At the upper portion this casing has radially inwardly extending walls 16 and 17 which are joined together and the upper partition has a segmental section 18 cut out, conforming to these walls, (note Figs. 7 and 2) this being to allow housing and action of the spring for operating the flint.

On one side, the casing 11 has an inwardly depressed section 19 which is formed concentric with the main outer portion and has shoulders 20 on each side (note Figs. 7 and 8).

In this portion there is also a recess 21 which is formed by a pair of parallel inwardly extending walls 22, with an inner wall 23. These are connected to the outward part of the wall 19 by a shelf-like structure 24 and 25 at the top and bottom of the recess (note Figs. 8 and 3).

A tubular cover sleeve 30 fits over the upper part of the casing 11 and this has a slot 31 formed in one side, there being a ring 32 threaded on the lower end of the cover sleeve. The upper part of the sleeve has a lower and an upper bead 33 and 34 pressed therein, the upper bead extending completely around the sleeve, the lower bead terminating at the slot 31. The upper part of the sleeve has the cover 45, this cover having a diametrically positioned hinge 46 with a lifting cover section 47 connected to the stationary section 48 by such hinge (note Figs. 2, 3 and 5.) The space 49 in the cover above the partition 12 is to accommodate the upper part of the flint carrying device, the friction wheel and the exposed part of the wick, as hereunder outlined.

At the bottom of the device there is a bottom partition 50 which is held to the partition 13 by bolts 51, these bolts being attached into the partition 13 and having nuts below the partition 50. The bolts are preferably shouldered to hold the partition 50 properly spaced from the partition 13. In the drawings there are three of these bolts illustrated (note Figs. 2, 3 and 9.) A bottom housing 52, preferably formed with cylindrical side walls, fits over the flange 53 of the partition 13 and has a closed lower end 54, this housing preferably being held in place by a screw 55 threaded into the bottom partition 50. The space 56 in the bottom housing accommodates various elements of the spring motor actuating and controlling mechanism, as hereunder detailed (note Figs. 2 and 3).

A tube 60 of comparatively small bore is connected at the top to the partition 12, this preferably extending slightly above such partition. This tube has an enlarged cylindrical lower end portion 61, such enlarged portion being secured to the partition 13. The tube 60 houses the main shaft 62 for operating the friction wheel 63 secured to the top thereof, the shaft having an enlargement or a bushing 64 forming a journal section at the top. The friction wheel 63 preferably rests on the shoulder on the top of the shaft 62 and bears also, if desired, on the upper edge of the tube 60 (note Fig. 3). This shaft extends downwardly and is journaled at its lower end 65 in the bottom partition 50. The enlarged tubular section forms the main housing for the spring motor, hereunder detailed.

A second tube 70 is connected to the lower partition 13 and extends upwardly, being connected to the shelf structure 24 which

forms the lower wall of the recess 21 (note Figs. 3, 8 and 9).

A fixed rod 71 extends through this tube 70, being secured at its lower end to the bottom partition 50 and at its upper end to the shelf 25 at the top of the recess 21. A sliding sleeve 72 is mounted on the rod 71 fitting freely inside of the tube 70 and this sleeve has a button structure, designated generally by the numeral 73, secured thereto at the top. This sleeve extends into the recess 21 so that the inner part of the button operates in such recess. The lower part of the sleeve is connected to an operating yoke designated generally by the numeral 74. A long coiled spring 75 fits outside of the sleeve 72 and bears at its upper end against the shelf 24 and at its lower end against the yoke 74. The function of this spring is set forth hereunder.

The liquid fuel, which is preferably highly inflammable, is filled into the liquid chamber through an opening 80 in the upper part of the casing 21 between the beads 33 and 34. Fitted between these beads there is a clamping spring 81 having a resilient sealing strip 82 mounted therein. This clamping spring has its ends 83 spaced apart substantially the width of the slot 31 so that the button 73 may slide upwardly between these ends, and when this clamping spring is turned so that the ends register with the opening 80, the liquid fuel may be poured in the casing 11, and in order to seal this opening, the clamping spring is then shifted so that the ends register with the slot 31. The center part of this spring with the sealing medium 82 then maintains a liquid-tight closure at the opening 80.

The mechanism for opening the lifting cover section 47 is substantially as follows: This is accomplished by the manual manipulation of the button 73, such button having a finger grip knurled portion 85 which has a rib 86 at the bottom extending downwardly over the portion of the casing 11 above the ring 32; and also has a rib 87 at the top with a hollow section 88 behind the finger grip and behind the rib 87. There is a shoulder 89 on the back of the finger button 73 which functions as hereunder mentioned. The rib 87 in its upward movement is adapted to extend over the portion 90 of the cover sleeve 30 above the slot 31. (Note Figs. 3, 4 and 7.)

A rack structure, designated generally by the numeral 91, is provided with a pair of rack bars 93 at the top, joined by a cross bar 94, and having a downwardly extending web 95 with an inwardly and an outwardly turned flange 96 and 97, the inwardly turned flange 96 having an aperture 98 therethrough to slide on the rod 71. The flange 97 is engaged by the shoulder 89 on the back of the button in the upward movement of the button when it is manually pressed upwardly, this giving

a certain lost motion, then lifting the rack. This rack is formed with the cross bar 94 and the rack arms 93 bent arcuate, as indicated by the numeral 99. This arcuate portion fits between the depressed section 19 of the casing 11 and the upper portion 90 of the sleeve 30, (Figs. 7 and 8) thus accurately guiding the rack construction.

The rack teeth 100 mesh with the rack teeth 101 on the segmental pinion 102 secured to the under side of the hinged lifting cover section 47 so that in the upward movement of the rack bar, the hinged section is open and turned completely back on the stationary section 48. A small coiled spring 103 is placed on the inside of the cover and has its ends 104 sliding in on the bottom part of the stationary section 48 and the lifting section 47 of the cover, this action keeping the cover snugly closed and giving a positive tension to hold the cover in closed position. The downward pull to automatically close the cover on releasing the button is by the spring 75 which is wound on the sleeve 72.

The mounting of the flint is substantially as follows: A flint holder 105 (note particularly Figs. 2, 21 and 22) has a hub 106 at the bottom and a shank 107 extending upwardly from the hub. A cross piece 108 is connected to the shank and has screw holes 109 for securing same to the top partition 12. As above mentioned, there being the segmental cut-out section 18 to accommodate the flint operating mechanism. An arched cover piece 110 forms a guide 111 for the flint 112 which is preferably formed cylindrical and there is a slot 113 leading into this guideway to accommodate the upper end of the spring. (Figs. 2, 21 and 22.)

The spring has a pressing section 114 which extends through the slot 113 and bears on the back of the flint. There is a coiled section 115 wound on the hub 106. A curved section 116 extends upwardly from the coil and is adapted to bear outwardly against the upper portion of the sleeve 30 substantially at the portion between the two beads 33 and 34. An inwardly extending arm 117 has at its end a cross piece 118 with a rearward bend 119, this being adapted to contact with the inner wall 17 of the casing 11, it being noted that the wall 17, together with the wall 16 (note Fig. 7) forms a segmental space to accommodate the flint operating mechanism in the upper part of the casing 11, and inside of the cover sleeve 30. The flint is in the position to bear against and be acted upon by the friction wheel 63 in the operation of such wheel.

The spring motor assembly is substantially as follows, having reference particularly to Figs. 2, 3, 4, 9, 11, 12, 14, 15, 16 and 17: An upper clutch element 120 is secured by a pin 121 or the like to the power shaft 62, this clutch being housed in the enlargement

61 of the tube 60. This clutch element has a segmental lug 124 on one side with a socket 125 therein which engages a prong 126 on the upper end of the spring 127. A lower clutch element 128 is rotatably mounted on the shaft 62 and has a segmental lug 129 mounted thereon (Figs. 9, 14, 15 and 16). The lower end of the clutch element 128 has a tongue 129' which fits in the jaws 130 of a sleeve 131; such sleeve has an upper ratchet element 132 with ratchet teeth 133 and is provided with a socket 134 to engage the lower prong 135 of the spring 127. This spring is coiled on the outside of the lower clutch element 128 and the sleeve 131. These are in separate pieces 80 having the tongue and the jaw for the purposes of assembly.

An abutment ring 136 is secured to the shaft 62 by a pin 137 and this is fitted in a recess 138 in the upper ratchet member 132 (note Figs. 3 and 14).

A winding block 140 is loosely mounted on the shaft 62 and has a recess 141 on the top to accommodate the abutment ring 136 and also has ratchet teeth 142 to engage the ratchet teeth 133 on the upper ratchet member 132. This block 140 has an enlarged recess 143 at the bottom which fits a light compression spring 143'. Such spring bears on the hub 144 of a ratchet wheel 145 secured by a pin 146 rigidly to the drive shaft 62.

A pair of helical threads 147 are formed in the winding block 140, these being deep grooves cut therein on opposite sides and making substantially one-half of a complete revolution from the bottom to the top of the block. As above mentioned, an operating yoke 74 is rigidly secured to the sleeve 72 which is raised by the thumb operating button 73. This yoke has yoke arms 148 with studs 149 facing inwardly on each of the arms and on each of the studs there is a roller 150 (note Figs. 10 and 11). These rollers fit in the helical threads 147.

To co-operate with the yoke and the winding block there is a sleeve 151 which is rotatably mounted on one of the bolts 51. This has a dog 152 mounted on the top, such dog having a beveled end 153. At the bottom of the sleeve 151 there is a pawl 154 which engages the teeth of the ratchet 145, the pawl being constantly pressed into engagement with such ratchet wheel by a coiled spring 155 wound on the sleeve 151, the lower end 156 of the spring engaging the pawl 154 and the opposite end 157 engaging or being secured to the bottom housing 52.

The manner of operation and functioning of the spring motor is substantially as follows: The upper clutch element 120, the lower clutch element 128, the sleeve 131 with the spring 127 wound on the two latter elements may be assembled on the shaft 62, and this shaft thrust upwardly through the tubes 60 and 61 before attaching the bottom housing 130

52. The friction wheel 63 may then be attached to the top above the top partition 12. In this assembly may be included the abutting ring 136, the winding block 140 and the ratchet wheel 145 with the spring 143'. The spring 127 is given an initial tension to the desired degree. The pawl 154 is constantly forced into engagement with the teeth of the ratchet wheel 145, thus holding the shaft 62 from rotation; and, due to the initial tension of the spring 127, the lugs 124 and 129 are in engagement. It is noted that these lugs are segmental so that when in engagement there is substantially a full semi-circle to allow 15 turning of one, relative to the other.

When the finger operated button 73 is thrust upwardly, which action, as above mentioned, opens the lifting cover section 47 by means of the rack and pinion device, it also 20 lifts the yoke 74 through the medium of the sleeve 72. Such action on account of the rollers 150 on the yoke arms 148 moving in the helical thread grooves 147 gives a partial rotation of the winding block 140, this being rotated substantially a full semi-circle. On account of the interengagement of the ratchet teeth 133 and 142, the turning of the winding block gives a half turn to the sleeve 131 and the lower clutch element 128. This 25 rotates the lower lug 129 until it engages the opposite face of the lug 124 so that it is normally engaged when at rest and manifestly this gives an increased tension to the winding of the spring 127.

35 When the yoke 74 comes to the upper part of the winding block 140 which is as far as it may travel on account of the limit of the movement of the finger operating button 73, this yoke engages the beveled end 153 of the dog 152, causing a rotation thereof and a rotation of the sleeve 151. Such action releases the dog 154 from the teeth of the ratchet wheel 145. Therefore the shaft 62 is free to rotate under the influence of the spring 127 a half 40 revolution or until the lugs 124 and 129 can engage. Such action causes the rotation of the friction wheel and the giving off of sparks due to the contact with the flint, thus igniting the liquid in the wick. So long as the 45 thumb operating button 73 is retained in its upper position, the lifting cover section 47 is retained open and the wick will continue to burn as long as the operator wishes it for lighting a cigar, cigarette or the like. Immediately, however, on releasing the operating button 73, this is shifted downwardly by the 50 action of the spring 75, closing the cover, and at the same time moving the yoke 74 downwardly, this action giving a reverse movement to the ratchet teeth 142; hence such reverse 55 action does not shift the sleeve 131. This brings the parts into position for the next operation. It is to be noted that the friction wheel at each operation is partly rotated and 60 at the next movement the rotation is contin-

ued so that the wheel acts evenly on the flint, and being subject to equal wear on its whole periphery.

The wick 160 extends upwardly through a ferrule 161 in the top partition 12 and has an exposed end 162 which becomes ignited by the sparks from the flint. The wick may be made of any suitable material such as asbestos and, following the usual practice, the space in the liquid chamber is preferably packed with cotton or other absorbent. It will be noted that although the device may be made comparatively small, substantially the size in diameter and length of a good sized fountain pen, nevertheless there is a relatively 75 large liquid chamber so that ample storage 80 is provided to saturate the wick.

In order to carry the device there is a clip 163 mounted on the cover sleeve 30, which may be utilized to hold the device in the pocket in the manner similar to a fountain pen. It will be seen by the construction and layout of my invention that the device is similar in shape to the usual fountain pen and it may be made of substantially the same size 85 as the standard pens now on the market. This gives a construction which is easily carried and of a desirable shape to handle.

It will be noted that a characteristic feature of my invention is that the device may be taken from the pocket and manipulated by the thumb or one of the fingers, this opening the cover and giving the additional tension to the spring and also releasing the spring motor to actuate the spark producing mechanism. This ignition of the spark is quite independent of any direct manual manipulation of the flint wheel, but it is done entirely through the spring motor which may be maintained at a tension to actuate the friction wheel at its best efficiency.

Another characteristic feature of my invention is the closure of the cover and extinguishing of the flame by such closure. This is done automatically on the release of the button 73 by the thumb or finger, as the spring 75 controls this action; also the spring 75 re-sets the threaded block by lowering this to the bottom of the device, whence it is in position for the next operation.

It will be noted that the construction of my lighter is of such a character that the parts may be readily assembled and disassembled when desired. As the bottom housing 52 is removable, it allows for the ready insertion of the main parts of the spring motor and the inspection and adjusting of these parts when necessary. Therefore, although the various elements must be made quite small to fit in a structure of the size desired, nevertheless, on account of the facilities for assembling, adjusting and repairing the small size is no particular disadvantage. Various other conveniences and improvements of my invention over the prior art will be apparent from the

above description together with the drawings.

Some of the detail features of my invention which are of importance involve the factor that the flint does not require adjustment, but is continually moved against the friction wheel until this is practically used up. Also the friction wheel rotates in the same direction with no reverse action. Therefore at each movement of this wheel, it is functioning to create a spark to light the wick, and there is no wear on the flint on account of any reverse action.

Another characteristic feature of my invention is that the mechanism for actually operating the friction wheel is mounted in a container and that the control device has its manually engaged element outside of the container.

Another feature is that the manually operated element may be moved at any desired rate of speed, such speed having no effect whatever on the speed at which the friction wheel operates, this being constant, as it is controlled by the spring and so designed to be at its maximum efficiency in each operation.

Another feature of my invention is that the spring motor arrangement for controlling the friction wheel is normally in an inoperative condition, that is, when the lighter is ordinarily carried in the pocket or in a handbag, there is no danger of the device operating and igniting the wick, as this can only be done when the button is manually operated.

Various changes may be made in the principles of my invention without departing from the spirit thereof, as set forth in the description, drawings and claims.

I claim:

1. A lighter comprising in combination a tubular casing structure with a chamber therein for liquid fuel, a wick extending into said chamber and having an ignitable end at one end of the casing, a flint and a friction wheel positioned adjacent said ignitable part of the wick, a compartment in the casing below and cut off from the liquid fuel chamber and having a spring motor mounted therein, a shaft extending from the motor through the fuel chamber to the friction wheel, a slideable device having a manually operable element extending outside of the casing, said device giving the motor a tension and releasing such motor, and means to limit the operation of the motor.

2. A lighter, as claimed in claim 1, the manually operable element comprising a finger engaging button mounted to slide in a recess in the casing, a sleeve connected to said button slideable on a rod, and means on the sleeve to tension the said spring.

3. A lighter comprising in combination an elongated tubular casing structure having a partition at the top with an ignitable wick

extending therethrough and having a friction wheel and a flint above said partition, there being an elongated liquid chamber in the said casing, a tubular structure extending through the casing from end to end and having a shaft mounted therein connected to the friction wheel, a spring motor mounted in said tubular structure and connected to the shaft, a second tubular structure extending longitudinally through the casing and having a motor tensioning and release device operable therethrough, said tensioning and release device having a manually operable element extending outwardly through the casing.

4. A lighter comprising in combination a tubular casing structure having a partition at the top and bottom, there being an upper recess and a lower recess in the sides of the casing, a flint holder and actuating spring mounted in the upper recess, a flint in such holder above the partition, a friction wheel, a wick extending through the upper partition, a manually operable device slidably mounted in the lower recess, a first tubular structure extending through the casing between the partitions and housing part of a spring motor, a shaft driven thereby, such shaft being connected to the friction wheel, a second tubular structure extending from the lower partition to the lower recess, and means forming an operable connection from the manually operable device to wind and release the spring motor.

5. A lighter, as claimed in claim 4, a base housing secured to the lower partition and having a winding device with the spring motor mounted therein, and also having part of the means forming the operable connection between the manually operable device and the spring motor mounted therein.

6. A lighter, as claimed in claim 4, a cover casing secured to the upper part of the tubular casing structure, a cover secured to the cover sleeve, and means to open and close part of the cover on the movement of the manually operable device.

7. A lighter comprising in combination a tubular casing structure having a partition at the top and bottom, there being an upper and a lower recess in the sides of the casing, a flint holder and an actuating spring mounted in the upper recess, a flint in said holder, a friction wheel above the top partition, a wick extending through the top partition, a bottom housing secured to the bottom partition, a first tube extending through the casing between the partitions and having part of a spring motor mounted therein at the lower part of such tube, a second tube extending through the casing from the bottom partition to the lower recess, a rod extending through the second tube and having a sleeve mounted thereon, a sliding button mounted

on the rod and sliding in the lower recess, a drive shaft extending from the bottom housing through the first tube and connected to the friction wheel, a threaded block rotatably mounted on said shaft, a yoke connected from the sleeve to rotate said block, means actuated by the block to wind the spring motor on sliding movement of the button, and means controlled by the yoke to release the shaft and allow actuation of the friction wheel.

8. A lighter, as claimed in claim 7, the means controlled by the yoke comprising a dog connected to a rotatable sleeve in the bottom housing, said dog being engaged by the yoke when in its upper position, and a pawl connected to the sleeve engaging a ratchet on the shaft, said pawl being disengaged by the movement of the dog.

9. A lighter, as claimed in claim 7, the means controlled by the yoke comprising a dog connected to a rotatable sleeve in the bottom housing, said dog being engaged by the yoke when in its upper position, a pawl connected to the sleeve engaging a ratchet on the shaft, said pawl being disengaged by the movement of the dog, an upper clutch element mounted on a shaft, a lower clutch element forming part of the spring motor, said clutch elements allowing a predetermined unwinding of the spring on release by the pawl.

10. In a lighter, a tubular casing with a liquid fuel chamber therein, a friction wheel, a flint and the exposed part of a wick at one end of the casing, a shaft connected to the friction wheel extending through the casing and having an upper clutch element connected thereto, a lower clutch element rotatably mounted on the shaft, said clutch elements having interengaging lugs to allow relative movement, a ratchet element operatively connected to the lower clutch element, a coiled spring interconnecting the ratchet element and the upper clutch element, a threaded winding block rotatably mounted on the shaft and having ratchet teeth to engage the teeth of the ratchet element, the said spring being under an initial tension, a manually operable device mounted on the casing to rotate the winding block and increase the tension of the spring, means controlled by the manually operable device to release the shaft and allow rotation thereof, such rotation being limited by the said clutch elements, and a restraining device for the shaft.

11. In a lighter, a tubular casing having a flint, a friction wheel and the exposed part of a wick at one end, a cover sleeve over the upper part of the casing and having a cover, part of such cover being movable and having segmental gears mounted thereon, a button slidably movable in a slot in the cover sleeve and rack bars connected to the button to slide therewith and actuate the segmental gears to

open and close the cover, and rotational means for the friction wheel, said means being controlled by the movement of the button.

12. In a lighter, a casing having a liquid fuel chamber therein, a flint, a friction wheel and the exposed part of a wick at one end of the casing, a shaft connected to the friction wheel, a spring motor having one part connected to the shaft and another part rotatably mounted thereon, a winding device mounted rotatably on the shaft to increase the tension of the spring of the motor, a restraining device for the shaft, means to actuate the winding device and to release the restraining device and to return such winding device to such initial position, the said shaft and friction wheel being always driven in one direction.

13. In a lighter, a casing having a liquid fuel chamber, a flint, a friction device and the exposed part of a wick at one end of the casing, said casing having an aperture adjacent the top for filling with liquid fuel, and a stopper device in the form of a split ring, said ring encircling the casing and slidably thereabout, said ring in one position forming a closure for the said opening and in another position exposing said opening for filling the casing with liquid fuel.

14. A lighter comprising in combination a tubular housing structure having a wick at the top, a flint and a friction wheel, a rotary spring motor located at the bottom of the housing, a shaft extending from the motor to the friction wheel, an intermediate chamber above the spring motor for liquid fuel, the wick extending therein, a manually operable slidable device extending partly outside of the housing to be engaged by the finger, the said device in one direction of movement winding the spring of the motor and releasing same to operate the friction wheel, and means to stop the motor after a predetermined movement.

15. A lighter comprising in combination a tubular housing structure having an upper partition with a wick extending therethrough, a flint and a friction wheel above the partition, a cover cap above the partition, a lower partition, a spring motor located mainly below said lower partition, a liquid fuel chamber between said partitions, a shaft extending from the spring motor to the friction wheel, a casing in the fluid chamber enclosing part of the spring motor and the said shaft, the wick extending into the chamber, a manually operable slidable device to be engaged by a finger extending partly outside of the said housing, means connecting said slidable device to the cover to open the cover in one direction of movement, means connecting the slidable device with the motor to tension the motor in one direction of move-

ment of the slidable device, the movement of said slidable device releasing the motor for operation, and means to stop the motor after a predetermined movement.

5. In testimony whereof I have signed my name to this specification.

JOHN C. ROMBACH.
